UNITED STATES PATENT OFFICE.

EDWARD LEEBERG, OF ROSELLE, NEW JERSEY.

FLUSH TANK.

1,426,203.

Specification of Letters Patent. Patented Aug. 15, 1922.

Application filed November 13, 1919. Serial No. 337,743.

To all whom it may concern:

Be it known that I, EDWARD LEEBERG, a citizen of the United States, residing at Roselle, in the county of Union and State 5 of New Jersey, have invented certain new and useful Improvements in Flush Tanks; and I do declare the following to be a full, clear, and exact description of the invention, such as will enable others skilled in the art to 10 which it appertains to make and use the same.

This invention relates generally to flush tanks, and more particularly to the valve mechanism for flush tanks.

One object of the invention is to provide 15 a flush tank with positive means for opening and closing the inlet and outlet valves and positive means for holding these valves in either opened or closed position, thus reducing leakage when the valves are closed to a 20 minimum.

Another object of the invention is to generally improve upon devices of this class by the provision of a comparatively simple, strong, durable and inexpensive construction, 25 one which will be efficient and reliable in operation, and well adapted to the purpose for which it is designed.

With these and other objects in view, the 30 invention consists of the novel features of construction, and the combination and arrangement of parts as will be hereinafter fully described and claimed.

In the accompanying drawings forming 35 a part of the specification, and in which similar reference characters designate like parts throughout the several views,

Figure 1 is a vertical longitudinal sectional view through a flush tank constructed 40 in accordance with this invention, showing the inlet valve closed and the outlet valve open;

Fig. 2 is a similar view showing the inlet valve opened and the outlet valve closed;

Fig. 3 is a detail sectional view taken substantially on the plane indicated by the line 3—3 of Fig. 2;

Fig. 4 is a detail sectional view taken substantially on the plane indicated by the line 4—4 of Fig. 3;

Fig. 5 is a perspective view of the bracket to which the outlet valve is hinged;

Fig. 6 is a perspective view of the lever which holds the outlet valve in opened position; and,

Fig. 7 is a perspective view of a portion of the link which connects the outlet valve

with the operating arm, showing more particularly the element which is engaged by the lever just referred to for holding the outlet valve in opened position. 60

Referring more particularly to the drawings, the numeral 1 designates a flush tank encased in a suitable box 2 and containing in its bottom openings 3 and 4. Disposed in and extending through the opening 3 is a bushing 5, the upper end of which is provided with a flanged head 6 between which and the upper surface of the bottom of the tank 1 is clamped a rubber gasket or washer 7 to insure a tight fit between the head of the bushing 5 and the bottom of the tank. Threaded upon the bushing 5 adjacent the lower end thereof and bearing against the lower surface of the box 2 is a nut 8, by which the bushing is held in place in 75 the opening 3. Extending longitudinally through the bushing 5 is an opening 9 which constitutes the inlet opening for the flush tank. The head 6 of the bushing is provided with a circular rib 10 around the edge 80 of the opening 9 and a spaced U-shaped rib 11 leaving a channel 12 between the latter and the rib 10. As shown the rib 10 is of less height than the rib 11. Formed integrally with the head 6 of the bushing 5 and 85 extending upwardly therefrom from the space included between the ends of the U-shaped rib 11 is an arm 13.

Pivoted to the arm 13 at 14 intermediate of its ends is a lever 15, the pivot 14 being 90 considerably closer to one end of the lever than it is to the other. The short arm of the lever 15 carries a weight 16, while the long arm of the lever is bent arcuately and has suspended from its free end a receptacle 95 17, which as shown is open at the top. The means for suspending the receptacle 17 to the lever 15 is loosely connected to the latter so that the receptacle will always assume an upright position irrespective of the position 100 that the lever is in. At a point located between the pivot 14 and the free end of the long arm of the lever 15 the latter is provided with a laterally extending lug 18, the purpose of which will be hereinafter described. 105

The inlet valve consists of a disk 19 having secured to its lower side in any suitable manner a rubber disk 20 and being provided on its upper side with an upright ear 21 to 110 which the lower end of a link 22 is pivoted. The upper end of the link 22 is pivoted at

23 to the lever 15 at a point on the short arm of the same but disposed angularly with respect to the general longitudinal direction of said short arm.

5 The arm 13 adjacent the point where it joins the head 6 of the bushing 5 is provided with an opening 24 communicating with the aforementioned channel 12, and having one end secured by soldering, threading or otherwise in this opening is a pipe 25 which extends in a diagonal and upward direction and has its upper end curved arcuately so as to discharge downwardly.

Disposed in and extending through the 15 opening 4 is a bushing 26 having a flanged head 27 at its upper end, between which and the upper surface of the bottom of the tank 1 is clamped a ring 28 and a rubber gasket or washer 29, the latter serving to provide 20 a tight fit between the bushing and the opening in the flush tank. Threaded upon the bushing 26 and bearing against the lower side of the box 2 is a nut 30, by which the bushing 26 is maintained in place in the 25 opening 4.

The ring 28 just described carries a laterally and horizontally extending extension 31 having formed integrally with the free end thereof an upright arm 32, the upper end 30 of which is bent horizontally to form a horizontally extending arm 33. Extending laterally and horizontally from the arm 33 is a wing 34 having an opening 35 therein, and extending upwardly from the upper 35 edge of the arm 33 is an apertured ear 36.

The outlet valve consists of a disk 37 provided with a lateral extension or arm 38, from one edge of which and at the free end thereof is struck upwardly an ear 39, which 40 is pivoted at 40 to the arm 32 of the bracket. Secured at the lower side of the disk 37 is a rubber disk 41, the securing means consisting of a clamping disk 42 and a screw 43 which extends through the three disks and 45 has its inner end threaded in a weighted head 44 disposed upon the upper side of the disk 37. When closed, the valve rests upon an annular rib 45 disposed at the edge of an opening 46 formed in the bushing 26. 50 The opening 46 is the outlet opening for the tank.

The head 44 is provided with an ear 47, to which the lower end of a link 48 is pivoted. The upper end of the link 48 is 55 pivotally connected to an arm 49 carried by a rock-shaft 50 mounted transversely of the tank and carrying suitable means for operating it, shown in dotted lines. The link 48 is slidable through the opening 35 in the 60 wing 34 and is provided adjacent its lower end with a downwardly extending hook 51. The hook 51 also extends outwardly and the portion of the link 48 disposed above the hook is inclined inwardly to form in effect 65 a wedge or cam.

Pivoted to the ear 36 by means of a pivot 52 is a lever 53, the short arm of which consists of a head 54 heavier than the long arm of the lever so that the head 54 will overbalance the short arm of the lever. The 70 inner edge of the head 54 is provided with an upwardly extending hook 55 adapted to interlock with the hook 51 carried by the link 48. The long arm of the lever 53 is positioned so that when the lever 15 rocks on 75 its pivot and its long arm descends, the lug 18 will contact with the same.

When the tank 1 is filled and the various parts of the mechanism are at rest, both of the valves are closed, the inlet valve being 80 held tightly upon its seat through the medium of the link 22 by the lever 15 which assumes a diagonal position by reason of the fact that the counter-weight 16 carried at the short arm of the lever overbalances the 85 long arm of the same and the receptacle 17 which will be understood is almost entirely filled with water. The outlet valve is maintained in closed position upon its seat by means of the weighted head 44. When in 90 normal position the hooks 51 and 55 are obviously not in engagement. With the parts in this position and it is desired to flush the tank, the rock-shaft 50 is rocked so as to swing the arm 49 and raise the link 48 and 95 open the outlet valve. During the upward movement of the link 48 the wedge-shaped portion of its hooked extension will engage the lower portion of the hook 55 of the head of the lever 53 and rock said lever upon its 100 pivot until the hook 51 passes beyond the hook 55. After this point has been passed the lever 53 will swing under the weight of its head 54 until the hook 55 is disposed beneath the hook 51 and engages the same so 105 as to hold the outlet valve and parts associated therewith in opened position. The outlet being opened the water in the tank will pass out of the same through the outlet opening 46, and as the water level lowers the 110 lever 15 will swing upon its pivot gradually opening the inlet valve. The rate of flow through the inlet valve is considerably less than the rate of flow through the outlet valve, and therefore the gradual opening of 115 the inlet valve will not prevent the tank from being quickly and completely drained. When the tank is completely drained so that the long arm of the lever 15 has descended to substantially a horizontal position, the lug 120 18 will contact with the long arm of the lever 53 and swing said lever upon its pivot so as to disengage the hook 55 from the hook 51. As soon as this is done the outlet valve will close under its own weight. As 125 the tank is filling the lever 15 will swing to its normal position, and the parts are automatically set for another operation. The parts of the lever 15 are proportioned so that in air when the receptacle 17 is empty 130

the long arm of said lever, will be overbalanced by the short arm, but when the receptacle is filled or almost filled with water, the long arm will overbalance the short arm. 5 However, when water is in the tank 1 the receptacle will be partly submerged in the water and the lever 15 will be balanced, the receptacle in effect floating upon the water and rising and falling with the level thereof. 10 but should the interlocking engagement of the hooks 55 and 51 be hard to break upon engagement of the long arm of the lever 53 by the lug 18 of the lever 15, movement of the lever 15 would be arrested. As the 15 level of the water in the tank 1 continues to descend, the receptacle 17 would no longer floats in the water of the tank but would be suspended from the lever 15 and therefore the dead weight of the receptacle 17 would 20 overbalance the weight of the counterweight 16 and the long arm of the lever 15 would thereby be caused to exert considerable downward pressure upon the long arm of the lever 53 and this increased downward 25 pressure would insure movement of the lever 53 to the position where its hook 55 would become disengaged from the hook 51.

The receptacle is maintained filled by means of the pipe or tube 25 which has its 30 discharge end placed so as to discharge into the receptacle and which has its inlet end connected to the head of the bushing 5 so as to take a small percentage of the water which passes through the inlet.

35 Heretofore flush tanks have been provided with ball valves and ball floats, but these have been very unsatisfactory, as the valves and floats corrode and become punctured, and the whole mechanism then becomes useless. In the mechanism above described this 40 disadvantage is overcome by reason of the fact that there are no valves or floats liable to puncture. In case the water or other fluid contained in the tank is of a nature 45 capable of corroding, the receptacle 17 may be made of glass or some other non-corrosive material. The opening and closing of the inlet and outlet valves is positive, and the valves are held in opened and closed position by positive means, so that there is little likelihood of the valves leaking or the various parts of the mechanism from properly functioning.

50 Various changes in form, proportion, and 55 in the minor details of construction may be resorted to without departing from the spirit of the invention as defined in the appended claims.

What is claimed is:

60 1. A device of the class described comprising a tank having inlet and outlet openings therein, an inlet valve for said inlet opening, a bushing disposed in and extending through said outlet opening and provided at its inner end with a head and a

valve seat, a ring clamped between said head and said tank and provided with a lateral extension, an upright arm formed integral with the outer end of said extension, a horizontal arm extending laterally from the upper end 70 of said upright arm, a guide carried by said horizontal arm, a weighted outlet valve hinged to said upright arm and seating upon said valve seat means for opening said outlet valve and including a link slidably received 75 in said guide, an overbalanced lever pivoted to said horizontal arm, interlocking elements carried by said link and said lever for holding said outlet valve open when opened to permit said tank to drain, means carried by 80 said link for swinging said lever as said valve is opened to position said elements for interlocking engagement and a movable member having its movement controlled by the level of the liquid in said tank and connected to said inlet valve to open the latter as the level of the liquid in said tank descends, said member being positioned for engagement with said lever when said tank 85 has been flushed to swing said lever and disengage said element to permit said outlet valve to close. 90

2. A device of the character described comprising a tank, having an inlet and an outlet, a valve for the inlet, actuating means 95 for the inlet valve including an arm pivotally mounted for vertical swinging movement, an open receptacle carried by said arm and constituting a float and adapted to receive a weight producing substance, an abutment extending from said arm, a valve for the outlet opening inwardly, actuating means for the outlet valve including a rod extending upwardly and having a latch engaging tooth, and a latch having a body 100 portion provided with a handle and a hook pivotally mounted off center to normally position the hook element in position for engaging the latch engaging tooth when the outlet valve is moved to an open position, 105 the handle extending to engage the abutment extending from said arm and interrupt downward swinging of the arm until said receptacle hangs as a dead weight and moves the latch to release the outlet valve. 110

3. A device of the character described comprising a tank having a valve controlled inlet and a valve controlled outlet, actuating means for the inlet valve, including an arm pivotally mounted for vertical movement, a float carried by said arm, actuating means for the outlet valve including a vertically disposed rod having a latch engaging tooth, a latch mounted above the outlet valve and normally in position for engaging the latch tooth of said rod when the rod is moved upwardly to open the outlet valve and retain the valve open, and a handle for said latch extending for engagement by said swinging arm to interrupt downward movement there- 125 130

of during emptying of the tank until the float hangs as a dead weight and moves the latch to release said rod and permit closing of the outlet valve.

- 5 4. A device of the class described comprising a tank having inlet and outlet openings therein, inlet and outlet valves for said inlet and outlet openings respectively, means for opening said outlet valve, means for holding said outlet valve open when opened, a lever fulcrumed intermediate of its ends in said tank and operatively connected with said inlet valve, one arm of said lever being positioned for engagement with said holding means to trip the latter and permit said outlet valve to close, a liquid receptacle suspended upon one arm of said lever and being open at the top, a counter-weight carried by the other arm of said lever, said 10 receptacle when containing liquid being heavier in air than said counter-weight but being balanced by said counter-weight when partly submerged in the liquid in said tank so that it will rise and fall with the level 15 thereof, and means for supplying said receptacle with a small percentage of the liquid which passes through said inlet valve and including a pipe extending from said inlet valve and having its discharge end positioned above said receptacle.

5. A device of the class described comprising a tank having inlet and outlet open-

ings therein, an outlet valve disposed in said outlet opening, means for operating said outlet valve, means for holding said outlet valve open when opened, a bushing disposed in and extending through said inlet opening and provided on its inner end with a valve seat and a channel surrounding the same, an upright arm formed on the inner end of said bushing, a lever pivoted intermediate of its ends to said arm and having one arm positioned for engagement with said holding means to trip the latter and permit said outlet valve to close, a counter-weight on one end of said lever and a receptacle on the other end thereof, said receptacle being open at the top and when containing liquid being heavier in air than said counter-weight but being balanced by said counter-weight when partly submerged in the liquid in said tank so that it will rise and fall with the level thereof, and inlet valve seating upon said valve seat, a connection between said lever and said inlet valve, and a pipe leading from said channel and having its discharge end disposed above said receptacle so as to supply the latter with a small percentage of the liquid which passes through said inlet valve.

In testimony whereof I have hereunto set my hand.

EDWARD LEEBERG.
